ROCK-AWAY HORSE

Joseph F. Oblazney, Camden, N.J.

Application June 4, 1958, Serial No. 739,820

2 Claims. (Cl. 280—1.177)

This invention relates to an amusement device, and more particularly to a rocking horse for use by children.

The object of the invention is to provide a rocking horse which is adapted to support a child, and wherein the horse of the present invention can be actuated in a novel manner so as to cause the horse to travel along a floor surface or other area with a highly pleasing and novel effect.

Another object of the invention is to provide a rock away horse which is adapted to support a child thereon, and wherein the rock away horse is constructed so that as the child moves his or her body back and forth, the device will travel along to thereby provide amusement and recreation to the user.

A further object of the invention is to provide a rocking horse which is extremely simple and inexpensive to manufacture.

Other objects and advantages will be apparent in the course of the following description.

In the accompanying drawing, forming a part of this application, and in which like numerals are used to designate like parts throughout the same:

Figure 1 is a side elevational view of the rocking horse of the present invention.

Figure 2 is a view similar to Figure 1 showing the parts in a different position.

Figure 3 is a front elevational view of the present invention.

Figure 4 is a sectional view taken on line 4—4 of Figure 1.

Figure 5 is a sectional view taken on line 5—5 of Figure 1.

Referring in detail to the drawing, the numeral 10 indicates the rocking horse of the present invention, and the rocking horse 10 includes a pair of spaced parallel curved or arcuate outer runners or rockers which are each indicated by the numeral 11. There is further provided a pair of spaced parallel inner rockers which are indicated by the numeral 12, and as shown in Figures 1 and 2, the outer rockers 11 are offset with respect to the inner rockers 12.

Arranged adjacent to the rear end of the rockers 11 are slots 13. Arranged adjacent the front end of the inner rockers 12 are slots 14. There is further provided front and rear axles or shafts which are indicated by the numerals 15 and 16. The front axle 15 extends through the front portions of the outer rockers 11 and through the slots 14 in the inner rockers 12. The rear axle 16 extends through the slots 13, and the rear axle 16 also extends through the rear portions of the inner rockers 12. As shown in Figure 4, sleeves 17 are mounted on the axles.

The numeral 18 indicates a support member which is adapted to provide a support for the child using the device, and extending upwardly from the support member 18 and secured thereto in any suitable manner is a head piece 19. The numeral 20 indicates a tail piece or back stop which extends upwardly from the rear of

2

the support member 18 which is secured thereto. The head piece 19 is provided with a handle 21 which is adapted to be gripped by the child sitting on the support member 18.

5 There is further provided a foot rest assembly which is indicated generally by the numeral 22, and the foot rest assembly 22 includes a first portion 23 which is secured below the support member 18 in any suitable manner, as for example by means of securing elements 24. Depending from the first portion 23 are spaced apart second portions 25, and foot engaging members 26 are arranged at the lower ends of the second portions 25.

The numeral 27 designates each of a pair of spaced apart rear legs, and a horizontally disposed cross piece 28 extends between the upper and rear legs 27 and is secured thereto or formed integral therewith. The cross piece 28 is secured below the support member 18 as for example by means of a securing element 29. The lower end of the rear legs 27 are connected to the sleeve 17 on the rear axle 16, as for example as shown in Figures 1 and 4. Secured to the lower front portion of the support member 18 is a plate 30, and the plate 30 may be secured in place by securing elements 31. The numeral 32 indicates each of a pair of spaced apart front legs, and the upper portions of the front legs 32 are interconnected by means of a top piece 33. The top piece 33 is hingedly connected to the plate 30 by means of a hinge 34.

Extending between the pair of front legs 32 and connected thereto in any suitable manner is a horizontally disposed brace 35, Figure 3. The numeral 36 indicates a guide member which has its front end connected to the brace 35, and a rod 37 is telescopically or adjustably connected to the guide member 36. The numeral 38 indicates a bracket which is secured below the support member 18 as at 39, and the bracket 38 is connected to the rear end of the rod 37. Spaced apart washers or discs 40 and 41 are mounted on a guide member 36 and rod 37, and a coil spring 42 is interposed or positioned between these discs 40 and 41.

From the foregoing it is apparent that there has been provided a rocking horse which will provide much amusement and recreation to the user. In use, a child is adapted to sit on the support member 18, and the handle 21 is adapted to be conveniently gripped in the child's hand. The feet of a child engages the members 26, and it will be seen that as the child rocks back and forth, the horse 10 will move forward so as to provide a device which is highly appealing and entertaining for the child.

50 Thus, it will be seen that there has been provided a children's rocking horse which has two sets of rockers and wherein the device creeps ahead as a child rocks on it. The tubing or sleeve arrangement as indicated by the numeral 17 serves to insure that there will be no binding in the various moving parts. The holes and slots in the rockers are arranged off center as shown in the drawing.

In use as a child rocks to the position shown in Figure 1, his weight or her weight is on the front legs 32, and since the front legs 32 are hinged at the top as at 34, and since the rockers 12 are free of the floor at this time, the rockers can fall ahead a distance allowed or permitted by the slots of the rockers, which may be about 4 inches for best performance, but this dimension can vary depending upon the size and height of the parts. As this takes place, more pressure is put in the pressure spring 42 so that the parts will assume the position shown in Figure 2 until the device rocks back from the position shown in Figure 2 to that shown in Figure 1. In the position shown in Figure 2, the device rests on the rockers 12 so that the rockers 10

are released whereby the rockers 11 are free as before. The pressure spring 42 then throws the front legs and rockers 11 forward into a position such as that shown in Figure 1. In each forward and back rock, the rockers move ahead from their previous positions.

In actual practice, the device may be made so that it is highly attractive, and the head 19 may be of any desired configuration. A child is adapted to have his or her feet rest on or engage the members 26.

The rocking horse of the present invention is arranged so that it creeps ahead as a child rocks on it. The front legs are hinged to the support member and the rear legs are secured solid to the support member. There is a pair of rockers on each side. Slots are arranged in each rocker so that when it is rocked forward, the inner rockers are free at the floor, and as the front legs are hinged, the horse leans forward, and the inner rockers move ahead the distance allowed in the slots and at the same time the front legs add more pressure to the coil spring. When it is rocked back, the outer rockers and the front legs are free of the floor and the compressed coil spring returns them back in position.

Minor changes and shapes, size and rearrangement of details coming within the field of invention claimed may be resorted to in actual practice, if desired.

I claim:

1. In a rocking horse, a pair of spaced parallel opposed outer rockers, a pair of spaced parallel inner rockers positioned between said outer rockers, each of said outer rockers being provided with a slot adjacent the rear end, each of said inner rockers being provided with a slot adjacent each front end, front and rear axles extending through said rockers and said axles extending through the respective slots in said rockers, sleeves mounted on said axles, a support member having a back stop and a head piece secured thereto, a handle connected to said head piece, a foot rest assembly including a first portion secured below said support member, spaced apart second portions depending from said first portion, foot engaging members at the lower ends of said second portions, a pair of spaced apart rear legs having their ends connected to the sleeves on the rear axle, a cross piece extending between the upper ends of said rear legs and said cross piece being secured beneath said support member, a plate mounted below the front portion of the support member, a pair of spaced apart front legs having their ends con-

ected to the sleeves of the front axle, a top piece connecting the upper ends of the said front legs together, said top piece being hingedly connected to the said plate, a horizontally disposed brace extending between said front legs and connected thereto, a guide member having a front end connected to said brace, a rod adjustably connected to said guide member, a bracket secured below said support member, said bracket being connected at the rear end of said rod, spaced parallel discs mounted on said guide member and rod, and a coil spring positioned between said pair of discs.

2. In a rocking horse, a pair of spaced parallel opposed outer rockers, a pair of spaced parallel inner rockers positioned between said outer rockers, front and rear axles extending through said rockers, sleeves mounted on said axles, a support member, a handle connected to said support member, a foot rest assembly secured below said support member, a pair of spaced apart rear legs having their ends connected to the sleeves on the rear 15 axle, a crosspiece extending between the upper ends of said rear legs and said crosspiece being secured beneath said support member, a plate mounted below the front portion of the support member, a pair of spaced apart front legs having their ends connected to the sleeves of 20 the front axle, a top piece connecting the upper ends of the said front legs together, said top piece being hingedly connected to the said plate, a horizontally disposed brace extending between said front legs and connected thereto, a guide member having a front end connected to said brace, a rod adjustably connected to said 25 guide member, a bracket secured below said support member, said bracket being connected at the rear end of said rod, spaced parallel discs mounted on said guide member and rod, and a coil spring positioned between 30 said pair of discs.
